CLAIM

The ornamental design for a lock body for a restraining strap assembly, as shown and described.

DESCRIPTION

FIG. 1 is a top, front, and left side perspective view of a lock body for a restraining strap assembly showing my new design, the broken-line depiction of the restraining strap being for illustrative purposes only and forming no part of the claimed design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof; and

FIG. 8 is a vertical cross-sectional view thereof, taken along line 8—8 of FIG. 2.

FIG. 1

FIG. 2

FIG. 3

FIG. 4

FIG. 5

FIG. 6

FIG. 7

FIG. 8
